UNITED STATES PATENT OFFICE.

CLAY MANTLEY, OF TORONTO, ONTARIO, CANADA.

RACING AND DIVING GAME.

Application filed May 19, 1924. Serial No. 714,333.

To all whom it may concern:

Be it known that I, CLAY MANTLEY, a subject of the King of Great Britain, residing at 296 Grace Street, in the city of Toronto, 5 in the Province of Ontario and Dominion of Canada, have invented a new and useful Racing and Diving Game, of which the following is a specification.

The invention relates to a new and useful 10 racing and diving game as described in the present specification and illustrated in the accompanying drawings which form part of the same.

The invention consists essentially of the 15 novel features of construction pointed out broadly and specifically in the claims for novelty following an explanation in detail of an acceptable form of the invention.

The objects of the invention are to bring 20 forth for the general use of the public a game that will be both amusing and instructive, at the same time attractive in appearance, compact in form; to provide a game dissimilar from the well-known and old 25 games awakening the popularity of this line and adapted to be installed in amusement parks, exhibitions and other public places of amusement, and generally to provide a device durable in construction, cheap in manufacture and efficient as a commercial value. 30

In the drawings,—

Figure 1 is a perspective view of the machine showing the working thereof, showing the stairway broken away.

Figure 2 is a perspective view of the governor.

Figure 3 is a perspective view of the doll carriage.

Figure 4 is a view of the catch mechanism and driving gear.

Like numerals of reference indicate corresponding parts in the various figures.

Referring to the drawings, the machine 1 is controlled by a wheel 2 having a handle 3 and a shaft 4 connecting the wheel 2 to a grooved wheel 5 having the recess 6.

The cable or rope 7 is inserted around the recess 6 of the grooved wheel 5 and secured around the pulley of the governor mechanism.

The governing mechanism is composed of two vertical shafts 9 and 10 attached to the frame 11 which is in turn suitably secured to the machine 1.

The vertical shaft 9 has a sleeve 12 on which is secured the pulley 8 and the gear 13,

and weights 14 are held on a resting plate 15 upon the sleeve 12. A pulley 16 and gear 17 are secured to the upper part of the shaft 9 above the frame 11 from which the driving belt or cable 18 is connected to the brake and winding apparatus.

The vertical shaft 10 has at top and bottom gears 20 and 19 respectively, meshing with the gears 13 and 17 of the shaft 9.

The brake and winding apparatus comprises a main shaft 21 which passes through as many of the machines as required, each machine irrespective of one another having a pulley wheel 22 loosely secured to the main shaft 21 and around which the driving belt 18 is secured. To each pulley wheel a drum 23 is connected and operated thereby for winding and unwinding the cable 24 which is controlling the movements of the doll.

The construction of the game itself comprises two pieces of sheet metal used as tracks and guide ways 25 and 26. These tracks are curved in such a way as is suitable for the game, while a stairway 27 is made on one side of the trackway 26 to give the appearance of the doll 28 mounting the steps while it is being pulled up by the cable 24.

The cable 24 is secured at one end to the drum 23 and runs tangent thereto to the full length of the machine. It then changes its course vertically upwards to the trackway 26, encircles a pulley 29, thence to a pulley 30 and from there downwardly through a guide 90 passage 31 and secured to a spring carriage 32.

Situated below the stairway and a little to one side, a tank of water 33 is located, formed of an elongated shape, and having a 95 runway 34 thereto.

The spring carriage 32 is composed of a flat metal side 35 having four pulley wheels 36, 37, 38 and 39 forming a guideway 40 for the guide passage 31. A spring 41 is held by the metal strip 42 at the top of the flat metal side 35, and having a catch 43 projecting therefrom, the cable 24 being secured to the spring carriage at 44.

This spring carriage is adaptable to be pulled to the topmost position of the machine, that is at pulley 30, where a block 45 is located to prevent the spring carriage from further progress. The spring carriage then returns to its former position at the 110 bottom of the steps, automatically winding up the cable 24 on its descent.

The doll carriage comprises a resting spring 46 for the doll 28 and a guide space 47, formed by the pulley wheels 48, 49, 50 and 51 for the trackway 26. A steadyng 5 guide member 52 is formed for the lower trackway 25, while a curved shaft 53 and wheel 54 is situated at the lower portion of the doll carriage and is used for the downward descent only when it slides into the guideway 34. The doll is bolted to the resting spring 46, so that on its movements it will have the appearance of being alive by the flexibility of the spring.

In the operation of the device, the machine is started by the turning of the wheel 2 which automatically turns the grooved wheel 6 having a cable connection to the lower pulley of the governor, while the upper pulley of the governor has a connecting cable to the pulley wheel of the brake winding apparatus, and through the intermeshing gears of the governor the speed of the cables are controlled, while the winding drum is prevented from unwinding by 25 means of the pulley wheel which is connected thereto.

The doll carriage which is prevented from falling back to its old position by means of the spring carriage, is pulled up 30 the incline. If by chance the controlling wheel is turned too fast and the gears in the governor are displaced, the carriage is automatically stopped and prevented from sliding down again by the brake in the winding apparatus.

When the doll carriage reaches the summit of the machine, the spring carriage, which has carried it up, is held back by the block at the end of the guide passage 31. 40 The doll carriage is then carried downwardly by gravity down the incline, the curved shaft and wheel 54, fitting into the guideway or groove 34, thence to the water tank where the doll, by means of suitable curves 45 of the trackway, dives into the tank and out again coming back into position for another trial.

In the game a plurality of these machines are used, each having its own control and 50 governor and the plan is to see which doll will reach the water before the others, thereby winning the race.

The device may, of course, be made in any suitable design or construction without departing from the main features of the invention as herein specified.

What I claim is:

1. In a game, a main frame having double trackways one above the other and parallel 60 to each other and constructed in a series of curves, a rigid stairway secured on one side of said trackways, and a spring carriage permanently held on to the upper trackway and slidale thereon, a puppet carriage 65 adapted to be held by said spring carrier,

a water tank at the base of said trackways, and a governor and control gear operating a brake comprising a drum and pulley wheel for winding and unwinding the cable controlling the movements of said puppet carriage up the incline of said trackways and releasing them therefrom. 70

2. In a game, a main frame having double trackways one above the other and parallel to each other and constructed in a series of curves, a rigid stairway secured on one side of said trackways, and a spring carrier comprising a plurality of pulleys forming a guideway thereinbetween for the upper trackway and a catch and spring mechanism 80 at the topmost corner thereof, a puppet carriage adapted to be held by said spring carrier, a water tank at the base of said trackways, and a governor and control gear operating a brake comprising a drum and pulley 85 wheel for winding and unwinding the cable controlling the movements of said puppet carriage up the incline of said trackways and releasing them therefrom.

3. In a game, a main frame having double trackways one above the other and parallel to each other and constructed in a series of curves, a rigid stairway secured on one side of said trackway, and a spring carrier permanently held on the upper trackway and 90 slidale thereon, a puppet carriage having a plurality of pulley wheels forming a guide member and a curved rod at its lower end fitting into a wheel and a guide member for the lower trackway and resting spring member having a doll securely fastened thereto, a water tank at the base of said trackways, and a governor and control gear operating a brake comprising a drum and pulley wheel for winding and unwinding the cable 105 controlling the movements of said puppet carriage up the incline of said trackways and releasing them therefrom.

4. In a game, a main frame having double trackways one above the other and parallel to each other and constructed in a series of curves, a rigid stairway secured on one side of said trackways and a spring carrier permanently held on to the upper trackway and slideable thereon, a puppet carriage adapted 110 to be held by said spring carrier, a water tank at the base of said trackways of an elongated shape and secured on a level with said upper trackway, and a governor and control gear operating a brake comprising a drum and pulley wheel for winding and unwinding the cable controlling the movements of said puppet carriage up the incline of said trackways and releasing them therefrom. 115

5. In a game, a main frame having double trackways one above the other and parallel to each other and constructed in a series of curves, a rigid stairway secured on one side of said trackways, and a spring carrier permanently held on the upper trackway and 120 125 130

- slideable thereon, a puppet carriage adapted to be held by said spring carrier, a water tank at the base of said trackways, and a governor comprising two main shafts having intermeshing gears, a sleeve on one of said shafts having weights resting thereon at its upper end and a pulley at its lower end and a cable securing said pulley to a control wheel operating a brake comprising a drum and pulley wheel for winding and unwinding the cable controlling the movements of said puppet carriage up the incline of said trackways and releasing them therefrom.
6. In a game, a main frame having double trackways one above the other and parallel to each other and constructed in a series of curves, a rigid stairway secured on one side of said trackways and a spring carrier permanently held on to the upper trackway and slideable thereon, a puppet carriage adapted to be held by said spring carrier, a water tank at the base of said trackways, and a controlling wheel secured to a governor by a cable connection, a driving belt secured to the governor and passing around a grooved wheel secured to a main shaft, and a drum on one side of said grooved wheel and secured to said main shaft.
7. In a game, a main frame having double trackways one above the other and parallel to one another and constructed in a series of curves, a rigid stairway secured on one side of said trackways, and a spring carrier permanently held on to the upper trackway and slideable thereon, a puppet carriage adapted to be held by said spring
- carrier, a water tank at the base of said trackways, and a control wheel and governor having a driving belt to grooved wheel secured to a main shaft and a drum for winding and unwinding a cable therearound having a ratchet wheel for holding said cable from slipping and a releasing catch for said cable.
8. In a game, a main frame having double trackways one above the other and parallel to one another and constructed in a series of curves, a rigid stairway secured on one side of said trackways, and a spring carrier slideable up an incline on a guide passage in which a cable is inserted, and a stop member at the top of said incline, a puppet carriage adapted to be held by said spring carrier, a water tank at the base of said trackways, and a control wheel and governor connected to a brake comprising a drum and pulley wheel for winding and unwinding the cable controlling the motion of said puppet carriage, a cable secured to a drum of said brake apparatus running parallel thereto to the length of said main frame and rising vertically therefrom to the topmost point of said trackway and around a plurality of pulleys through said guide passage and secured to said spring carrier.

In testimony whereof I have affixed my signature this 13th day of May, 1924 at the city of Toronto.

CLAY MANTLEY.
